PROCESS FOR CRACKING HYDROCARBON
OILJean Delattre-Seguy, Chicago, Ill., assignor to
Universal Oil Products Company, Chicago, Ill.,
a corporation of South Dakota

Application March 23, 1927. Serial No. 177,811

3 Claims. (Cl. 196—66)

This invention relates to improvements in process and apparatus for cracking oil and refers more particularly to a process and apparatus wherein the vapor is evolved by the conversion of hydrocarbon oil under heat and pressure and the reflux condensate formed by fractionation of said vapors are retreated for further conversion under conditions independent from those to which the hydrocarbon oil was primarily subjected.

10 In the drawing:

The single figure is partly a sectional and partly an elevational side view of an apparatus which can be used to carry out the process of the invention.

15 Referring to the drawing, the raw oil to be treated is charged through line 1 by means of pump 2 and through line 3 controlled by a valve 4 into a heating coil 5 as positioned in furnace 6 heated by furnace 7. The oil which is raised in the coil 5 to conditions of temperatures and pressure suitable to promote conversion is then passed through line 8 controlled by valve 9 into reaction chamber 10, which has been shown 20 as of a vertical type but may be of any other desired type. In reaction chamber 10 the oil constituents separate into liquid residue and vapors. The liquid residue contains pitch and coke-like particles and this liquid residue can be withdrawn from the reaction chamber 25 through line 11 controlled by valve 12. The vapor separated in reaction chamber 10 is withdrawn therefrom through line 13 and is controlled by a valve 14 whereby they are directed into a separately heated chamber 15. The 30 vapors may also be passed from reaction chamber 10 into the separate chamber 15 through by-pass line 16 in which is interposed a vapor pump 17 controlled by valves 18.

40 The secondary chamber 15 can be of any desirable type and heated by any suitable means and I have shown in the drawing a vertical chamber heated on its sides and having its lower and upper ends outside the heating zone. The 45 sides of said chamber are heated by means of combustion gases evolved in furnace 19 heated by burners 20 which gases pass out through flue 21 to stack 22.

In said chamber 15 the vapors evolved in the 50 primary conversion zone of the process are forced to bubble through a pool of liquid reflux condensate as will hereinafter be described and the mixture of vapors and reflux condensates are further converted, but the vapors are withdrawn 55 from the top of chamber 15 through vapor line

23 controlled by valve 24 and pass into the dephlegmator 25 where they are subjected to fractionation in the usual manner. This dephlegmation can be helped by introduction to dephlegmator 25 of cooling mediums. Vapors 60 which remain uncondensed in the dephlegmator 25 pass out of the top thereof through line 26 controlled by valve 27 into condenser 28 and thence through line 29 controlled by valve 30 into receiver 31 which is provided with 65 the usual gas and liquid drawoffs 32 and 33 controlled respectively by means of valves 34 and 35. The receiver is also provided with level gauges and pressure gauges not shown.

Referring back to the reflux condensate formed 70 in dephlegmator 25, said reflux condensate is withdrawn from the bottom thereof through line 36 leading to a hot oil pump 37 controlled by valves 38. By means of this pump the reflux condensate can be discharged through line 39 75 controlled by valve 40 into the upper portion of the secondary treating chamber 15, wherein said reflux condensate is subjected to further treatment in the presence of vapors evolved in the primary heating and reaction zone respectively 80 shown at 5 and 10. The vapors evolved from the treatment of the reflux condensate in chamber 15 pass off through line 23 into dephlegmator 25 with the vapors evolved in the primary conversion zone after they have been retreated 85 in the secondary treating chamber 15.

The unvaporized oil from the secondary treating chamber 15 is withdrawn from the bottom of the chamber through line 41 controlled by valve 42 and is returned to the heating tubes 90 5 of the primary conversion zone after commingling with the charging stock in line 3.

If desired the hot oil pump 37 can be bypassed through line 43 controlled by valve 44.

Also I have shown a line 45 controlled by valve 46 connecting lines 39 and 41 whereby a portion of the reflux condensate may be returned from dephlegmator 25 to the heating coils 5 without passing through the secondary treating chamber 15.

If desired a portion of the charging stock introduced into the system by pump 2 can be diverted into the dephlegmator 25 through line 47 controlled by valve 48 and this portion combines with the reflux condensate in dephlegmator 25 and is thereby preheated and the mixture is treated in treating chamber 15 as hereinbefore described for the reflux condensate.

As a feature of the invention the conditions of treatment to which the vapors evolved in 110

100

105

110

the primary heating zone and the reflux condensate formed in the dephlegmator are subjected in the treating chamber 15 are preferably more severe than the conditions maintained on the primary conversion zone. The temperature maintained in chamber 15 by means of furnace 19 is preferably higher than the maximum temperature to which the oil was subjected during its passage through the heating coil 5 and reaction chamber 10.

Simultaneously the pressure maintained on the secondary treating chamber 15 is higher than that maintained on the heating coil 5 and reaction chamber 10 and this increased pressure can be obtained by the proper manipulation of the charging pump 2, valves 3 and 48 of the reflux pump 37 and valves 40 and 46 and of the vapor pump 17 and the valve 24 on the vapor line 23, and also of valve 42 on the liquid drawoff 41 from the treating chamber 15.

By manipulation of said valves the pressure on the treating chamber 15 can be maintained higher than that on the heating coil 5 and reaction chamber 10 and at the same time the pressure on the dephlegmator 25 and the balance of the system can be the same as or lower than the pressure on said treating chamber 15.

Since the vapors and reflux condensate from the material to be treated in chamber 15 are lighter than the material treated in the primary conversion zone and since to obtain further conversion in chamber 15 the temperature therein is preferably higher than that maintained through heating coil and chamber 10 the pressure in the chamber 15 is preferably higher than that on the balance of the system to prevent undue formation of noncondensable gases and coke.

I have provided chambers 10 and 15 with suitable manholes for cleaning and the chamber 15 with an additional drawoff 49 controlled by the valve 50 whereby heavy material can be drawn off from said chamber and evacuated.

The relative degree of pressure and temperature maintained on the various parts of the system depend mainly on the characteristics of the materials treated and of the products desired. It can be noted here that the more severe the conditions of temperatures and pressure maintained on the treating chamber 15, the larger percentage of unsaturates and aromatic compounds will be formed in the process.

Furthermore the conditions of temperature and pressure on the treating chamber 15 may be such as to cause a substantially complete conversion of these materials into hydrocarbon fixed gases without undue formation of coke.

For instance, in one method of operation the oil in the heating coil 5 will be raised to a temperature from 700 to 900° F. under a pressure

of from 300 to 500 pounds while the vapors and reflux condensate in treating chamber 15 can be subjected to a temperature of from 950 to 1200° F. under a pressure from 600 to 1000 pounds more or less.

I claim as my invention:

1. A process for cracking hydrocarbon oil comprising raising the oil to a cracking temperature in a heating zone, delivering the heated oil to an enlarged reaction zone wherein conversion takes place, in maintaining a body of reflux condensate in a second enlarged zone, in passing the vapors from said first enlarged zone into said second enlarged zone, in direct physical contact therewith in subjecting the vapors and reflux condensate in said second zone to a higher temperature than that maintained in said heating zone, in subjecting vapors issuing from said second zone to reflux condensation, in passing the reflux condensate separated from the vapors to said second enlarged zone to supply the body of reflux condensate maintained therein, in maintaining a pre-determined superatmospheric pressure on the oil in said heating zone and first enlarged zone while maintaining a higher super-atmospheric pressure on the body of reflux condensate and vapors in said second enlarged zone.

2. A hydrocarbon oil cracking process which comprises heating charging oil to cracking temperature in an initial heating zone, discharging the heated oil into a separating zone and separating evolved vapors from unvaporized oil therein, passing said vapors to a second heating zone containing liquid oil of lower boiling point than said initial heating zone wherein said vapors and oil contact, maintaining said second zone at higher temperature and pressure than said separating zone to effect cracking therein, removing cracked vapors from said second zone and subjecting the same to dephlegmation, and condensing the dephlegmated vapors.

3. A hydrocarbon oil cracking process which comprises heating charging oil to cracking temperature in an initial heating zone, discharging the heated oil into a separating zone and separating evolved vapors from unvaporized oil therein, passing said vapors to a second heating zone containing liquid oil of lower boiling point than said initial heating zone wherein said vapors and oil contact, maintaining said second zone at higher temperature and pressure than said separating zone to effect cracking therein, removing cracked vapors from said second zone and subjecting the same to dephlegmation, passing reflux condensate resulting from said dephlegmation to said second zone to constitute said oil of lower boiling point, and condensing the dephlegmated vapors.
